UNITED STATES PATENT OFFICE.

THOMAS B. SCRIBNER, OF ORLAND, CALIFORNIA.

WINDOW-CURTAIN HOLDER.

1,255,472.

Specification of Letters Patent.

Patented Feb. 5, 1918.

Application filed March 8, 1917. Serial No. 153,426.

To all whom it may concern:

Be it known that I, THOMAS B. SCRIBNER, a citizen of the United States, residing at Orland, in the county of Glenn and State 5 of California, have invented certain new and useful Improvements in Window-Curtain Holders; and I do declare the following to be a full, clear, and exact description of the invention, such as will enable others 10 skilled in the art to which it appertains to make and use the same.

This invention relates to improvements in means for holding window curtains, portières, and the like in position.

15 The principal object of the invention is to provide a very simply constructed adjustable holder of the above set forth character.

An additional object is to provide a curtain holder having an adjustable clamp whereby the device may be secured to a window or door frame in the proper position to correctly hold the curtain or the like.

Still another object is to provide a device 25 of this character having a pivoted curtain retaining member so that the curtain may be reliably held regardless of the position of the clamping member.

With these and many other objects in view, the invention resides in the novel features of construction, combination and arrangement of parts which will be herein more particularly described and claimed and shown in the drawings wherein:

35 Figure 1 represents an elevation of a portion of a window frame showing the invention attached to the sill thereof;

Fig. 2 is a similar view of a portion of a door frame, the device being attached to the 40 jamb thereof;

Fig. 3 is a horizontal section on the line 3—3 of Fig. 2;

Fig. 4 is an enlarged detail section on the line 4—4 of Fig. 2; and

45 Fig. 5 is a vertical section taken substantially on the plane of the line 5—5 of Fig. 4.

From the accompanying drawing, wherein similar reference characters designate like parts throughout the several views, it 50 will be seen that the invention comprises broadly an adjustable clamping member 1 which is to be disposed on a door or window frame, and a curtain retaining member 2, the latter being substantially in the form of 55 a hook or other device which will effectively

receive and retain the curtain or portière. By providing an adjustable clamping member, the device may be secured to any width window or door frame, or the trim thereof.

The clamping member consists of a relatively stationary jaw 3 and a movable jaw 4 which is slideable toward and away from the first mentioned jaw to receive window frames or other supporting members of various widths and thicknesses. The stationary jaw has a shank 5 formed integrally therewith and extending substantially at right angles therefrom, said shank being preferably cylindrically enlarged and provided with a transverse opening 6, the bore 65 of which extends parallel to a plane passing through the stationary jaw.

The movable jaw 4 has an elongated cylindrical shank 7 disposed parallel thereto and extending a considerable length beyond the same. In plan view, the member from which the movable jaw is formed is substantially U-shaped, one of the arms being longer than the other, the long arm extending into said opening 6. It will be 70 seen that the movable jaw is rigidly guided in its movement by the shank 7 being disposed in the opening 6 and that it is held in position with respect to the stationary jaw by means of a set screw 8. The latter is 75 carried by the shank 5 of the stationary jaw and extends through a threaded opening into the bore 6. This construction is shown particularly in Fig. 5.

The free end of the shank 5 is slightly reduced as shown at 9 and also provided with a threaded socket 10, the latter extending longitudinally of the shank as shown. This reduced portion 9 forms a pivot stud which is disposed in a plane at right angles to the 90 line of movement of the sliding jaw 4. The above mentioned curtain retaining member 2 is pivoted upon the stud 9 and adapted to freely rotate thereon.

The curtain retaining member is formed 100 of a rod which has one end bent upon itself to form a hook 11, and the curtain or other drapery to be held in position is disposed in this hooked portion. The other end of the bar or rod has a collar 12 formed integrally 105 therewith, the bore of which extends at right angles to the longitudinal plane of the main portion of the member and is adapted to receive the pivot stud 9 of the shank 5. After the collar 12 has been placed on the 110

pivot stud a retaining screw 13 is threaded in the socket 10 and the enlarged head thereof holds the curtain retaining member in position while at the same time allowing it to rotate around its pivot.

The operation of one of these curtain holders is very simple, it being first secured to either a portion of a window frame or door frame, depending upon the kind of curtain to be held. When the clamping member is secured to the vertical trim of either the door or window frame, the device is disposed substantially horizontally as shown in Fig. 2. On the other hand, when the clamping member is attached to a window sill or similar portion of a window, the same is positioned vertically, while the curtain retaining member is disposed horizontally as shown in Fig. 1. The curtain retaining member, however, may be disposed in any other position since it may readily be moved about its pivot. By the use of such a device as above described it is unnecessary to drive nails or the like into the door and window frames to hold the usual curtain cords.

I claim:

1. A window curtain holder of the class described comprising an adjustable clamp adapted to be secured to the vertical or horizontal portions of a window frame and composed of two jaws, one being movable toward and from the other and a curtain retaining member rotatably mounted on one of said jaws in a plane substantially at

right angles to the path of movement of the clamping jaws.

2. A window curtain holder of the class described comprising an adjustable clamping member having a sliding jaw movable 40 toward and away from the stationary jaw, a pivot stud extending from the stationary jaw in a plane at right angles to the path of movement of the sliding jaw, and a curtain retaining member rotatably mounted 45 on said stud.

3. A window curtain holder of the class described comprising a stationary jaw having a shank extending substantially at right angles thereto and provided with an opening disposed parallel to said jaw, a movable jaw having a straight elongated shank extending parallel to the jaw and slidably disposed in said opening, a pivot stud formed of the shank of said stationary member and having a threaded socket therein, a curtain retaining member having a hook on one end, its other end being enlarged and provided with an opening to receive said pivot stud, a retaining screw disposed in 50 said threaded socket, and a set screw carried by the shank of the stationary jaw to lock the sliding jaw thereto.

In testimony whereof I have hereunto set my hand in the presence of two subscribing 65 witnesses.

THOMAS B. SCRIBNER.
